FUEL BURNER CONTROL SYSTEM

John M. Wilson, Minneapolis, Minn., assignor to
 Minneapolis-Honeywell Regulator Company,
 Minneapolis, Minn., a corporation of Delaware

Application March 5, 1942, Serial No. 433,494

20 Claims.

(Cl. 158—28)

This invention is directed broadly to an automatic control system for a fluid fuel burner, and more specifically to a control system in which an electric motor controls the various timing sequences in automatically starting and stopping the operation of the fuel burner.

One of the main objects of the present invention is to provide a system of the above type in which a control motor is energized upon a demand for burner operation to simultaneously energize the ignition device and cause a delivery of fuel to the burner, to open a safety switch in the event that combustion is not established after said motor has been operating for a predetermined period of time, but if combustion is established before the time has elapsed to continue operating until it reaches a running position in which it remains until the demand for burner operation has been satisfied at which time it closes a return switch to cause it to return to its original or starting position, at the same time shutting down the burner.

A further object in the invention is to cause the control motor to close the return switch at the same time that the safety switch is opened so that the control motor will then return to its original position while the safety switch remains open.

A further object of the invention is to operate the automatic control system by means of an electric motor having a stator and rotor, the stator assuming a first position when the motor is deenergized and being movable to a second position when the motor is energized due to a reaction between the rotor and the stator. The system is further arranged so that each time the control motor is deenergized it operates to close the return switch for the purpose of returning the motor and the control to their original or starting position, it being understood that the control motor will not close this return switch when it is in its starting position.

A further object of the invention is to provide a simplified motor operated burner control system which has all of the necessary features of safety, these features of safety being provided by the control motor thus eliminating the necessity for any electro magnetic relays.

These and other objects of the invention will readily become apparent as the following specification is read in the light of the accompanying drawing in which

Figure 1 illustrates a control circuit incorporating the various features of my invention,

Figure 2 is a diagrammatic representation of my control motor and a control unit in the form of a plurality of cams which are operated thereby to perform various control functions, and

Figure 3 is a view similar to Figure 2 showing the cams in a different operative position.

Referring now to the drawing the reference numeral 10 indicates generally an electric motor having a stator 11 and a rotor 12. This motor is of the unidirectional type and has a constantly energized main winding 13 and a shading winding 14. As long as the circuit to the shading winding 14 is open, the motor is stationary, but as soon as the circuit is closed thus short circuiting the winding 14, the motor will start to operate. Motors of this type are old and well known in the art.

The stator 11 is rotatably mounted on the same axis 14 as is the rotor 12, the stator being biased into engagement with a stop 15 by means of the biasing spring 16, shown diagrammatically in Figure 2. When the shading winding 14 is energized a starting torque is developed and the reaction between the rotor 12 and the stator 11 causes the stator to rotate in a counter-clockwise direction and engage the stop 17. The stator 11 will remain in this position until the winding 14 is deenergized at which time it will return to its original position and engage the stop 15 under the influence of the biasing spring 16. The rotor 12 is connected through the reduction gears 19 to a rotatable shaft 20 indicated in the dotted lines in the drawing. Cams 21, 22, 23 and 24 are mounted on the shaft 20 for rotation thereby. The shaft 20 and the cams 30 form a control unit which may be designated by the reference numeral 25. An operating member 26 is freely pivoted on the shaft 20 and is adapted to be moved back and forth by the stator 11 as it moves between its two stops 15 and 17. For the purpose of simplifying the drawing the operating member 26 has been shown as connected to the stator 11 by means of a link 27, but it will readily be appreciated that in actual practice the shaft 20 extends parallel to or concentric with the axis 14 about which the rotor 12 rotates and that therefore the operating member 26 may be directly connected to the stator 11. In any event it will be clear from the drawing that the operating member 26 is moved back and forth as the motor shading winding 14 is energized and deenergized causing the stator 11 to move back and forth between the two stops 15 and 17.

The cam 21 is adapted to control the two electric switches 28 and 29 which are shown as comprising a pair of resilient blades 30 and 32 which are biased to their straight line position and a resilient blade 31 which is located between these two blades and biased upwardly, as shown in Figure 2. The blade 31 has an extension carrying an insulating member 33 which rides on the surface of the cam 21. The cam 21 has a low portion 34 which permits the blade 31 to move upwardly under the influence of its own bias both opening the switch 29 and closing the switch

28. As the cam 21 rotates in a clockwise direction the insulating member 33 will engage the intermediate portion of the cam surface 35 and force the blade 31 downwardly in which position it will cause closure of the switch 29, but will not be moved down far enough to open the switch 28. By further rotation of the cam 21 the insulating member 33 will engage the high portion 36 thereof and force the blade 31 downwardly to a position where it opens the switch 28 while maintaining the switch 29 in closed position.

The cam 22 is adapted to control the switch 38 which is shown as comprising a resilient contact blade 39 biased to its horizontal position and a second resilient blade 40 biased upwardly as shown in Figure 2 and carrying at its free end an insulating member 41 which cooperates with the surface of the cam 22. When the insulating member 41 engages the low surface of the cam 22 as shown in Figure 2 the switch 38 is open but when the cam 22 rotates to a position where the high part of the cam engaged insulating member 41 the switch 38 is closed as shown in Figure 3.

The cam 23 controls the switch 43 which is essentially similar to the switch 38, being composed of a resilient blade 44 which is biased to horizontal position and a resilient blade 45 which is biased upwardly as shown in Figure 3, the blade 45 carrying at its free end an insulating member 46 which cooperates with the surface of the cam 23. When the high surface of the cam 23 engages the insulating member 46 the switch 43 is closed as shown in Figure 2 but when the low portion of the cam 23 engages the insulating member 46 the switch 43 is open as shown in Figure 3.

The cam 24 operating in conjunction with the operating member 26 is adapted to control the return switch 48 and a pair of safety switches 49 and 50. Considering first the return switch 48, this switch is shown as comprising a pair of resilient contact blades 51 and 52 which are biased to open position, but which may be moved to closed position by means of the lever 53 which is shown as being pivoted at 54. When once closed the switch 48 is latched in closed position by means of the latching surface 55 on the latch member 56 which is pivoted at 57 and biased to its latched position by means of the biasing spring 58. The operating link 59 is pivotally connected at one end to the lever 53 for transmitting motion from the operating member 26 to the lever 53 for moving the return switch 48 to closed position. When the latch 56 and link 59 are in their upper position as shown in Figure 3 the link 59 is so positioned that when the control motor 10 is deenergized and the stator 11 returns to its position in engagement with the stop 15 the operating member 26 will be rotated to force the link 59 to the left as seen in the drawing, resulting in the closure of the return switch 48 and the latching thereof on the latching surface 55 on the latch member 56. When the latch member 56 and the link 59 are in their lower position as seen in Figure 2 the link 59 is out of the path of movement of the operating member 26 so that even though the control motor is deenergized and the operating member rotates in a clockwise direction it will have no effect upon the return switch 48. The latch member 56 is controlled in its position by means of a pin or roller 61 which rides upon the surface of the cam 24. As long as this roller 61 is in engagement with the

high surface 62 of the cam 24 as shown in Figure 2, it positions the link 59 so that it cannot be engaged by the operating member 26, but when this roller engages any part of the remaining portion of the cam surface the link 59 is positioned as shown in Figure 3, at which time the deenergization of the control motor 10 will cause the operating member 26 to close and latch the return switch 48.

10 The safety switch 50 is shown as comprising a pair of resilient contact blades 64 and 65 which are biased to closed position as shown. The safety switch 49 is formed by a resilient contact blade 66 which is biased to its horizontal position and a second contact blade 67 which is biased downwardly to open circuit position but which is normally held in circuit closed position by means of the latch 68 which engages the free end of the blade 67. The latch 68 is pivoted at 69 and when it rotates in a counter-clockwise direction it releases the free end of the blade 67 which moves downwardly to open the switch 49 and which through the pin 70 opens the switch 50. It will therefore be seen that 20 the removal of latch 68 from engagement with blade 67 causes the opening of both the safety switches 49 and 50.

The latch 68 is adapted to be operated by means of a trip member 72 which is freely pivoted at 30 73 to one end of a lever 74. The lever 74 is in turn pivoted at 75 and at its other end carries a roller 76 which cooperates with the surface of the cam 24. A biasing spring 77 holds the lever 74 in such a position that the roller 76 is always 35 in engagement with the cam 24. When the roller 76 engages the low portion 71 of the cam 24 the lever 74 rotates in a counter-clockwise direction about its pivot 75 and raises the entire trip member 72 to the position shown in dotted lines in 40 Figure 2 of the drawing. With the trip member 72 in this position it can be seen that when the control motor 10 is deenergized and the operating member 26 rotates in a clockwise direction it will 45 engage the left hand end of the trip member 72 and cause it to rotate in a counter-clockwise direction about its pivot 73 and cause the cam surface 78 to engage the pin 79 thereby rotating the latch 68 in a counter-clockwise direction and releasing the contact blade 67 which opens both 50 the switches 49 and 50. When the roller 76 on the lever 74 is in engagement with any other portion of the cam surface except the low portion 71 the trip member 72 will be lowered to such a 55 position that it is out of the path of movement of the operating member 26. Therefore, the only time during which deenergization of the control motor can operate to open the safety switches 49 and 50 is when the roller 76 is in engagement with the low portion of the cam surface 71.

60 The cam 24 carries an abutment 80 which is adapted to pass freely beneath the trip member 72 and link 59 but which is adapted to abut the end 81 of the lever 53 as indicated in Figure 3. This causes the control motor 10 to stall until 65 the lever 53 is removed from engagement with the abutment 80 thereby permitting continued rotation of the control motor.

Figure 1 illustrates a circuit diagram of a control system utilizing the control motor and control unit shown in Figures 2 and 3. Any one of 70 a number of various standard condition responsive devices may be utilized for sensing a demand for burner operation and thus initiate operation of the control system as a whole, but for the purposes of illustration the control system has been

shown under the command of a room thermostat indicated generally at 85 and which comprises a bimetallic element 86 fixed at one end and carrying at its free end a resilient contact blade 87 and a second contact blade 88. These two contact blades are adapted to cooperate respectively with the stationary contacts 89 and 90, the arrangement being such that on a decrease in temperature the bimetallic element 86 first causes contact blade 87 to engage the stationary contact 89 and then at a slightly lower temperature causes the contact blade 88 to engage the stationary contact 90.

The reference numeral 92 indicates generally a combustion responsive device which is diagrammatically illustrated and which causes a switch arm 93 to engage its cold contact 94 in the absence of combustion and its hot contact 95 in the presence of combustion. This device is not intended to be a calibrated device but it is intended to be of the type in which the switch arm 93 moves in response to the appearance or disappearance of flame at the burner. Such devices are old and well known in the art.

The switches 28, 29, 38, 43, 48, 49, and 50 which are operated by the various cams in Figures 2 and 3, have been given the same reference numerals in Figure 1. The switch arm 98 and stationary contact 89 correspond to the same elements in Figures 2 and 3. This switch arm 98 is adapted to be operated by the stator 11 as the control motor is energized and deenergized. The switch arm is so arranged that when the control motor is deenergized and the stator is up against the stop 15 the switch arm 98 is in open position whereas when the control motor is energized and the stator is against the stop 17 the switch arm 98 is moved into engagement with the stationary contact 99.

Although this control system could be utilized for the control of various types of fuel burners, for the purposes of illustration, it has been shown in connection with an oil burner. The reference numeral 100 therefore indicates the usual oil burner motor and the reference numeral 101 indicates an ignition device for igniting the fuel delivered to the burner by the burner motor 100.

The electrical power for operating the system is supplied by the two line wires 102 and 103 to which the main winding 13 of the control motor 10 is constantly connected through the conductors 104 and 105. As explained above the rotation of the control motor 10 is controlled entirely by short circuiting the shading winding 14.

Operation

If the burner motor 100 and ignition device 101 are deenergized the temperature in the room in which the room thermostat 85 is located will begin to fall and first cause the resilient blade 87 to engage the stationary contact 89. This will not affect the system in any way due to the fact that the switch 88, 90 is open and the switch 98, 99 open. The temperature in the room will therefore continue to decrease until the bimetallic element 86 causes the contact 88 to move into engagement with the stationary contact 90. This completes a starting circuit for short circuiting the shading winding 14. This circuit extends from one side of the winding 14 through conductor 107, the safety switch 49, conductor 108, contact 89, contact blades 87 and 88, contact 90, conductors 109, 110 and 111, switch 28, conductor 112, combustion responsive switch arm 93, cold contact 94 and conductors 113 and 114 back to the other side

of the shading winding 14. This will result in the energization of the control motor 10 and the resultant reaction between the stator 11 and rotor 12 will cause the stator to rotate from engagement with the stop 15 into engagement with the stop 17. This is the condition which is shown in Figures 1 and 2. It will be noted that at the time the control motor 10 is originally energized the control unit 25 is in its starting position in which the insulating element 33 engages the low portion 34 of the cam 21 thereby resulting in the closure of the switch 28 and the opening of the switch 29. The motor control switch 38 is in open position and the ignition switch 43 is closed. It will be noted however, that the motor control switch 38 is in series with the ignition device 101 so that both the burner motor 100 and the ignition device 101 are deenergized at this time. The latch member 56 is in its tripped position due to the fact that the roller 61 is engaging the high portion 62 of the cam 24. Therefore the return switch 48 is open. The trip member 72 is in its lower position due to the fact that the roller 76 on the lever 74 is not engaging the low portion 77 of the cam 24. The contact blade 67 is latched on the latch 68 and therefore the safety switches 49 and 50 are in the closed position.

As pointed out above, the switch arm 98 engages its stationary contact 99 as soon as the control motor 10 is energized and the stator rotates into engagement with the stop 17. Closure of this switch establishes a holding circuit for the shading winding 14 which is independent of the switch blade 88 and the contact 90. This circuit extends from one side of the shading winding 14 through conductor 107, safety switch 49, conductor 108, contact 89, flexible switch blade 87, bimetallic element 86, conductor 115, switch arm 98, stationary contact 99, conductors 116, 110 and 111, switch 28, conductor 112, combustion responsive switch arm 93, cold contact 94 and conductors 113 and 114 back to the other side of the shading winding 14. Therefore after the control motor 10 has once been energized the switch blade 88 may move out of engagement with the stationary contact 90 without affecting the energization of the control motor 10.

Operation of the control motor 10 will cause the cams 21, 22, 23 and 24 to rotate in a clockwise direction. The first operation performed by the cams is that the cam 22 causes closure of the motor control switch 38. This causes energization of the burner motor 100 by means of a circuit extending from the line wire 102 through conductor 118, safety switch 50, conductor 119, burner motor switch 38, conductors 120 and 121, burner motor 100 and conductors 122 and 123 back to the other line wire 103. The ignition device 101 will be simultaneously energized by a circuit extending from the line wire 102 through conductor 118, safety switch 50, conductor 119, burner motor switch 38, conductors 120 and 124, ignition switch 43, conductor 125, ignition device 101, and conductors 126 and 123 back to the other line wire 103. Therefore the burner motor and the ignition device will be energized substantially immediately upon the energization of the control motor 10.

At substantially the same time the insulating member 33 will ride up on the end of the intermediate portion 35 of the surface of the cam 21 which will cause the blade 87 to move downwardly and close the switch 28 while maintaining switch 29 is closed. This establishes a holding circuit for the shading winding 14 which is

independent of the combustion responsive switch arm 93. This holding circuit extends from one side of the shading winding 14 through conductor 101, safety switch 49, conductor 108, contact 89, switch blade 87, bimetallic element 86, conductor 115, switch arm 98, contact 99, conductors 116, 118 and 111, switches 28 and 29 in series and conductors 128 and 114 back to the other side of the shading winding 14.

After a predetermined time during which the fuel at the burner should ignite, the insulating member 48 will drop off the high side of the cam 23 thereby resulting in the opening of the ignition switch 43. After a second predetermined time necessary to establish definitely whether the fuel is going to remain ignited following the deenergization of the ignition device, the insulating member 33 rises upon the high side 36 of the cam 21 thereby opening the switch 28 while maintaining the switch 29 in the closed position. It will be recalled that the switch 28 was in the original starting circuit for the control motor 10 and also in the holding circuit which was closed after operation in the control motor 10 has started.

If combustion has not been established at this time the combustion responsive switch arm 93 will remain in engagement with the cold contact 94 and the control motor 10 will therefore become deenergized. It will be noted that when the control unit 25 has been rotated far enough to close the switch 29 and then open the switch 28 that the high point 82 of the cam 24 will have passed from beneath the roller 81 on the latch member 56 and therefore this member will have positioned the link 59 up into the path of movement of the control member 26. Therefore, when the control motor 10 is deenergized at this time and its stator rotates back into engagement with the stop 59 the resultant clockwise rotation of the control member 26 will cause it to strike the link 59 and move the lever 53 to the left thereby latching the return switch 48 in the closed position on the latching surface 55 of the latched member 56.

Also at the time the switch 28 is opened by the cam 21 the roller 76 on the lever 74 will be in the low portion 77 and the cam 24 which means that the tripping member 72 will be in its upper position at which time it will also be in the path of movement of the operating member 26. Therefore, when the control motor is deenergized at this time the resultant movement of the operating member 26 will cause a counter-clockwise rotation of the tripping member 72 which will then engage the pin 78 on the latch 68 and move this latch from engagement with the resilient blade 87 thereby permitting it to open both safety switches 49 and 50.

Thus, if combustion is not established at the end of the trial ignition period when the switch 28 is opened by the cam 21 then both of the safety switches 49 and 50 are latched in open position and the return switch 48 is latched in the closed position. Opening of the safety switch 49 immediately deenergizes the burner motor, the ignition device 101 having previously been deenergized by the opening of the ignition switch 43. Opening of the safety switch 49 opens the thermostat circuit which prevents the closure of any circuit through the shading winding 14 by the thermostat until the two safety switches have been manually reclosed. The closing of the return switch 48 establishes a circuit through the shading winding 14 which extends from one side of this winding through conductor 130, return

switch 48, and conductor 131 back to the other side of the shading winding 14. This therefore immediately reenergizes the control motor 10 which continues rotating until the high portion 56 of the cam 24 engages the roller 81 on the latch lever 56 and moves this lever to its tripped position resulting in the opening of the return switch 48 and the subsequent deenergization of the control motor 10. At this time however, it will be noted that the link 59 has been moved out of the path of movement of the operating member 26 as has been the tripping member 72. The control motor 10 therefore remains deenergized and cannot be reenergized until the safety switch 49 is manually reset. Also, the burner motor 100 and the ignition device 101 remain deenergized until the safety switch 50 has been manually reset. When the trouble which resulted in the failure of the burner to properly ignite has been remedied and the two switches 49 and 50 have been manually reset, the control motor 10 will again be energized through the room thermostat 85 and the circuits described above will again be closed to cause the system to attempt to start.

Assume now that the control motor 10 has been reenergized and that the control unit 25 has first closed the burner motor switch 38 and then opened the ignition switch 43 and that it has also closed the switch 29 for establishing the holding circuit for the control motor 10 and then has opened the switch 28 in the starting and holding circuits. If combustion has been established at this time then the combustion responsive switch arm 93 is in engagement with the hot contact 95. The shading winding 14 then remains energized following the opening of the switch 28 by means of a circuit extending from one side of the shading winding 14 through conductor 101, safety switch 49, conductor 108, contact 89, switch blade 87, bimetallic element 86, conductor 115, switch arm 98, contact 99, conductors 116, 118 and 132, hot contact 95, combustion responsive switch arm 93, conductor 112, switch 28 and conductors 128 and 114 back to the other side of the shading winding 14.

The above circuit has therefore prevented the deenergization of the control motor 10 at this time and it continues to rotate until the abutment 80 engages the end 81 on the lever 53. This stops the control unit 25 in its running position as shown in Figure 3 and stalls the control motor 10. The parts then remain in this position as long as the resilient thermostat blade 87 engages its stationary contact 89 and as long as the combustion responsive switch arm 93 is in engagement with its hot contact 95.

If either of these switches are opened however, the control motor 10 is deenergized and as the link 59 is in its upper position at this time, the control member 26 will close and latch the return switch 48. The tripping member 72 at this time will be in its lower position due to the fact that the roller 76 will not be in the low portion 77 of the cam 24. Therefore, the deenergization of the control motor at this time will not operate to unlatch the resilient blade 87 and the safety switches 49 and 50 will remain closed. The only time that the deenergization of the control motor is operative to cause the operating member 26 to unlatch the two safety switches 49 and 50 is at the time the switch 28 is opened by the cam 21, at which time the roller 76 is in the low portion 77 of the cam 24 and the tripping member 72 is in its raised position in which it is in the path of movement of the operating member 26.

The return switch 48 being in its closed position the control motor 10 will operate to rotate the control unit until the high portion 62 of the cam 24 operates to lower the latching member 56 and release the return switch 48 to move to its open position. This occurs in the starting position of the control unit 25 as illustrated in Figure 2 of the drawing.

It will be noted that the return switch 48 will be moved to closed position upon deenergization of the control motor except when the control motor is in its starting position. Therefore, should there be a momentary power failure when the control unit 25 is in any position other than a starting position the return switch 48 will be latched closed with the result that the control motor will continue to operate until it returns to its starting position, at which time, if the room thermostat is still calling for heat, the control will go through its normal starting cycle. It will be noted further that as the control motor rotates the control unit 25 from its running position to its starting position it provides for a sufficient time delay to clear the combustion chamber of all combustible fumes which might result in an explosion when the ignition device is reenergized. Therefore, even though the burner motor is reenergized when the power comes on following a power failure it will be deenergized by opening the motor switch 38 and then the control motor will provide for a scavenger period before the ignition device can again be reenergized when the system attempts to start.

Many changes and modifications of this invention will undoubtedly occur to those who are skilled in the art and I therefore wish it to be understood that I intend to be limited by the scope of the appended claims and not by the specific embodiment of my invention which is disclosed herein for the purpose of illustration only.

I claim as my invention:

1. In a motor operated fuel burner control system, a control motor, hot and cold combustion switches, a motor operated switch, a condition responsive switch, a first circuit controlling the energization of said control motor, said circuit means including said condition responsive switch, cold combustion switch and motor operated switch, electrical fuel delivery means rendered operative by said control motor upon energization thereof, a normally closed safety switch in control of said fuel delivery means, a circuit including said hot combustion switch for maintaining energization of said control motor, means operated by said control motor after a predetermined time for opening said motor operated switch in said first circuit, and means responsive to the opening of said first circuit for opening said safety switch in the event that said hot combustion switch is not closed when said motor operated switch is opened.

2. In a motor operated fuel burner control system, a control motor, hot and cold combustion switches, a motor operated switch, a condition responsive switch, a first circuit controlling the energization of said control motor, said circuit means including said condition responsive switch, cold combustion switch and motor operated switch, electrical fuel delivery means and ignition means rendered operative by said control motor upon energization thereof, a normally closed safety switch in control of said fuel delivery means and ignition means, a circuit including said hot combustion switch for maintaining energization of said control motor, means operated by

said control motor after a predetermined time for opening said motor operated switch in said first circuit, means responsive to the opening of said first circuit for opening said safety switch in the event that said hot combustion switch is not closed when said motor operated switch is opened, means operated by the continued operation of said control motor, in the event that said safety switch is not opened, for terminating ignition, and means operative to stop said control motor in a position in which said electrical means is delivering fuel and said ignition means inoperative.

3. In a motor operated fuel burner control system, a control motor, hot and cold combustion switches, a motor operated switch, a condition responsive switch, a first circuit controlling the energization of said control motor, said circuit means including said condition responsive switch, cold combustion switch and motor operated switch, electrical fuel delivery means rendered operative by said control motor upon energization thereof, a normally closed safety switch in control of said fuel delivery means, a second motor operated switch closed by said control motor upon energization thereof, a pair of circuits either of which can maintain energization of said control motor independently of said cold combustion switch, the first of said pair of circuits including the first and second motor operated switches in series, the second of said pair of circuits including said hot combustion switch and second motor operated switch in series, means operated by said control motor for opening said first motor operated switch a predetermined time after the closing of said second motor operated switch, and means responsive to the opening of said first circuit for opening said safety switch in the event that said hot combustion switch is not closed when said first motor operated switch is opened.

4. In a motor operated fuel burner control system, a control motor, a condition responsive switch for controlling the energization of said control motor, a fuel delivery device, means operated by said control motor upon energization thereof for rendering said fuel delivery device operative to deliver fuel to a burner, a normally closed safety switch, means controlled by said motor for opening said safety switch a predetermined time after said fuel delivery means has been rendered operative, the opening of said safety switch rendering said fuel delivery means inoperative, means including a combustion responsive means for preventing the opening of said safety switch in the event that combustion is established first, means operated by said control motor for thereafter stopping said control motor in a position to maintain said fuel delivery means operative, and means including a return switch for energizing said control motor upon opening of said condition responsive switch for returning said motor to a position where it renders said fuel delivery means inoperative.

5. In a motor operated fuel burner control, a control motor, a control unit operated thereby, fuel control means operated by said control unit for controlling the flow of fuel to a burner, said control unit having a starting position in which no fuel is flowing to the burner, a control circuit including a condition responsive switch for energizing said control motor to cause it to move said control unit toward a running position, means operated by said motor for stopping said control unit in its running position, said fuel

control means being operated by said control unit as it leaves its starting position for causing a flow of fuel and maintaining said flow as it continues to its running position, a return switch for said control motor, circuit responsive means for closing said return switch when said control circuit is deenergized for any reason for causing operation of said control motor, said fuel control means terminating said fuel flow as said control unit is moved by said control motor out of its running position toward its starting position, and means operated by said control unit for opening said return switch when said control unit has reached its starting position.

6. In a motor operated fuel burner control, a control motor, a control unit operated thereby, fuel control means operated by said control unit for controlling the flow of fuel to a burner, means for igniting said fuel, said control unit having a starting position in which both said fuel control means and igniting means are inoperative, a control circuit including a condition responsive switch for energizing said control motor to cause it to move said control unit to a running position, means operated by said control unit as it moves out of its starting position for operating said fuel control means to cause delivery of fuel to the burner and for energizing said igniting means and then deenergizing said igniting means before said control unit reaches its running position, means operated by said control unit for stopping said motor when said control unit reaches its running position, a return switch for said control motor, circuit responsive means for closing said return switch when said control circuit is deenergized for any reason for causing operation of said control motor, said fuel control means terminating said fuel flow as said control unit is moved by said control motor out of its running position toward its starting position, and means operated by said control unit for opening said return switch when said control unit has reached its starting position.

7. In a motor operated fuel burner control, a control motor, a control unit operated thereby, an electrical device which, when energized, causes the delivery of fuel to a burner, a first switch for energizing said device actuated by said control unit, said control unit having a starting position in which said first switch is open, a normally closed safety switch in control of said fuel delivery device, a control circuit including a condition responsive switch for energizing said control motor to move said control unit toward a running position, means operated by said control unit for closing said first switch as said control unit leaves its starting position, means positioned by said control unit when it reaches an intermediate position for opening said safety switch, means responsive to the establishment of combustion at said burner for preventing such opening of the safety switch if combustion is established first, means operated by said control unit for stopping said control motor when said control unit reaches its running position, a return switch for said control motor, circuit responsive means for closing said return switch when said control circuit is deenergized for any reason for causing said control motor to move said control unit to its starting position, said control unit opening said first switch when it moves out of its running position, and means operated by said control unit for opening said return switch when said control unit has reached its starting position.

8. In a motor operated fuel burner control sys-

tem, a control motor having a rotor and a stator, said stator being rotatable coaxially with said rotor between first and second positions, means biasing said stator to its first position, a control unit, reduction gearing through which said control unit may be operated by said rotor, an electrical device which, when energized, causes the delivery of fuel to a burner, a first switch in control of said last named device operated by said control unit, said control unit having a starting position in which said first switch is open, an operating circuit for said control motor including a condition responsive switch, the reaction between the rotor and stator upon the establishment of said operating circuit causing said rotor to rotate in one direction and said stator to rotate in the opposite direction against its bias to its second position, said control unit being moved by said rotor from its starting position to a running position, said control unit closing said first switch as it moves from its starting position, a fixed stop, means associated with said control unit engaging said fixed stop to stall said control motor, a return switch for said control motor, means operated by said stator as it returns to its first position under the influence of its bias when said operating circuit is broken causing removal of said stop and closure of said return switch, circuit means established by said return switch for energizing said control motor to move said control unit to its starting position, said control unit opening said first switch as it moves from its running position, and means operated by said control unit for opening said return switch thereby deenergizing said control motor when said control motor reaches its starting position.

9. In a motor operated fuel burner control system, a control motor having a rotor and a stator, said stator being rotatable coaxially with said rotor between first and second positions, means biasing said stator to its first position, a control unit, reduction gearing through which said control unit may be operated by said rotor, an electrical device which, when energized, causes the delivery of fuel to a burner, a first switch in control of said last named device operated by said control unit, a second switch operated by said control unit, a safety switch in control of said electrical device, said control unit having a starting position in which said first switch is open and said second switch closed, a first operating circuit for said control motor including a condition responsive switch and said second switch, the reaction between the rotor and stator upon the establishment of said operating circuit causing said rotor to rotate in one direction and said stator to rotate in the opposite direction against its bias to its second position, said control unit being moved by said rotor from its starting position toward a running position, said control unit closing said first switch as it moves from its starting position and then opening said second switch as it moves to an intermediate position to interrupt said first operating circuit for the control motor, interruption of said first operating circuit causing said stator to return to its first position under the influence of its bias if said control motor is deenergized at this time, means operated by said stator for opening said safety if said control motor is deenergized when said control unit is in its intermediate position, a second operating circuit for said control motor including a closed hot combustion switch, said last named circuit preventing deenergization of

said control motor at the intermediate position of said control unit provided combustion is established before said control unit reaches its said intermediate position, and means for stopping said control motor when it reaches its running position.

10. In a motor operated fuel burner control system, a control motor having a rotor and a stator, said stator being rotatable coaxially with said rotor between first and second positions, means biasing said stator to its first position, a control unit, reduction gearing through which said control unit may be operated by said rotor, an electrical device which, when energized, causes the delivery of fuel to a burner, a first switch in control of said last named device operated by said control unit, a second switch operated by said control unit, a safety switch in control of said electrical device, said control unit having a starting position in which said first switch is open and said second switch closed, a first operating circuit for said control motor including a condition responsive switch and said second switch, the reaction between the rotor and stator upon the establishment of said operating circuit causing said rotor to rotate in one direction and said stator to rotate in the opposite direction against its bias to its second position, said control unit being moved by said rotor from its starting position toward a running position, said control unit closing said first switch as it moves from its starting position and then opening said second switch as it moves to an intermediate position to interrupt said first operating circuit for the control motor, interruption of said first operating circuit causing said stator to return to its first position under the influence of its bias if said control motor is deenergized at this time, means operated by said stator for opening said safety if said control motor is deenergized when said control unit is in its intermediate position, a second operating circuit for said control motor including a closed hot combustion switch, said last named circuit preventing deenergization of said control motor at the intermediate position of said control unit provided combustion is established before said control unit reaches its said intermediate position, a fixed stop, means associated with said control unit engaging said fixed stop to stall said motor when said control unit reaches its running position, a return switch, said stator closing said return switch when said control motor is deenergized and also removing said fixed stop whereby said control motor is reenergized to return said control unit to its starting position, and means operated by said control unit for opening said return switch when said control unit reaches its starting position.

11. In a motor operated fuel burner control system, a control motor having a rotor and a stator, said stator being rotatable coaxially with said rotor between first and second positions, means biasing said stator to its first position, a control unit, reduction gearing through which said control unit may be operated by said rotor, an electrical device which, when energized, causes the delivery of fuel to a burner, a first switch in control of said last named device operated by said control unit, said control unit having a starting position in which said first switch is open, an operating circuit for said control motor including a condition responsive switch, the reaction between the rotor and stator upon the establishment of said operating circuit causing said rotor to rotate in one direction and said stator to rotate

in the opposite direction against its bias to its second position, said control unit being moved by said rotor from its starting position to a running position, said control unit closing said first switch as it moves from its starting position, a fixed stop, means associated with said control unit engaging said fixed stop to stall said control motor, a return switch for said control motor, means operated by said stator as it returns to its first position under the influence of its bias when said operating circuit is broken causing removal of said stop and closure of said return switch, circuit means established by said return switch for energizing said control motor to move said control unit to its starting position, said control unit opening said first switch as it moves from its running position, means operated by said control unit for opening said return switch thereby deenergizing said control motor when said control motor reaches its starting position, and means preventing said stator from reclosing said return switch when said control motor is deenergized upon returning said control unit to its starting position.

12. In a motor operated fuel burner control system, a control motor having a rotor and a stator, said stator being rotatable coaxially with said rotor between first and second positions, means biasing said stator to its first position, a control unit, reduction gearing through which said control unit may be operated by said rotor, an electrical device which, when energized, causes the delivery of fuel to a burner, a first switch in control of said last named device operated by said control unit, a second switch operated by said control unit, a safety switch in control of said electrical device, said control unit having a starting position in which said first switch is open and said second switch closed, a first operating circuit for said control motor including a condition responsive switch and said second switch, the reaction between the rotor and stator upon establishment of said operating circuit causing said rotor to rotate in one direction and said stator to rotate in the opposite direction against its bias to its second position, said control unit being moved by said rotor from its starting position toward a running position, said control unit closing said first switch as it moves from its starting position and then opening said second switch as it moves to an intermediate position to interrupt said first operating circuit for the control motor, interruption of said first operating circuit causing said stator to return to its first position under the influence of its bias if said control motor is deenergized at this time, means operated by said stator for opening said safety if said control motor is deenergized when said control unit is in its intermediate position, a second operating circuit for said control motor including a closed hot combustion switch, said last named circuit preventing deenergization of said control motor at the intermediate position of said control unit provided combustion is established before said control unit reaches its said intermediate position, means for stopping said control motor when it reaches its running position, and a return switch for said control motor, said stator closing said return switch if said control motor is deenergized when said control unit is in its intermediate position whereby said control unit will be returned to its starting position while said safety switch remains open.

13. In a motor operated fuel burner control system, a control motor having a rotor and a stator, said stator being rotatable coaxially with

said rotor between first and second positions, means biasing said stator to its first position, a control unit, reduction gearing through which said control unit may be operated by said rotor, an electrical device which, when energized, causes the delivery of fuel to a burner, a first switch in control of said last named device operated by said control unit, a second switch operated by said control unit, a safety switch in control of said electrical device, said control unit having a starting position in which said first switch is open and said second switch closed, a first operating circuit for said control motor including a condition responsive switch and said second switch, the reaction between the rotor and stator upon the establishment of said operating circuit causing said rotor to rotate in one direction and said stator to rotate in the opposite direction against its bias to its second position, said control unit being moved by said rotor from its starting position toward a running position, said control unit closing said first switch as it moves from its starting position and then opening said second switch as it moves to an intermediate position to interrupt said first operating circuit for the control motor, interruption of said first operating circuit causing said stator to return to its first position under the influence of its bias if said control motor is deenergized at this time, means operated by said stator for opening said safety if said control motor is deenergized when said control unit is in its intermediate position, a second operating circuit for said control motor including a closed hot combustion switch, said last named circuit preventing deenergization of said control motor at the intermediate position of said control unit provided combustion is established before said control unit reaches its said intermediate position, means for stopping said control motor when it reaches its running position, a return switch for said control motor, said stator closing said return switch if said control motor is deenergized when said control unit is in its intermediate position whereby said control unit will be returned to its starting position while said safety switch remains open, and means preventing reclosure of said first operating circuit for said control motor when said control unit has returned to its starting position until said safety switch has been reclosed.

14. In a motor operated fuel burner control, a control motor, a control unit operated thereby, an electrical device which, when energized, causes the delivery of fuel to a burner, igniting means for the fuel, an ignition switch in control of said igniting means, a first switch in control of both said igniting means and fuel delivery device, both said switches being actuated by said control unit, a normally closed safety switch in control of said fuel delivery device and igniting means, said control unit having a starting position in which said first switch is open, a control circuit including a condition responsive switch for energizing said control motor to cause it to move said control unit towards a running position, said control unit closing said first switch as it moves from its starting position and then later opening said ignition switch, said ignition switch having been closed by said control unit prior to closure of said first switch, means positioned by said control unit as it reaches an intermediate position for opening said safety switch, means responsive to the establishment of combustion at the burner for preventing such action if combustion is established first, means operated by said control unit

for stopping said control motor when said control unit reaches its running position, a return switch for said control motor, circuit responsive means for closing said return switch when said control circuit is deenergized for any reason for causing said control motor to move said control unit to its starting position, said control unit opening said first switch when it moves out of its running position, and means operated by said control unit for opening said return switch when said control unit has reached its starting position.

15. In a motor operated fuel burner control system, a control motor having a rotor and a stator, said stator being rotatable coaxially with said rotor between first and second positions, means biasing said stator to its first position, a control unit, reduction gearing through which said control unit may be operated by said rotor, an electrical device which, when energized, causes the delivery of fuel to a burner, a first switch in control of said last named device operated by said control unit, a second switch operated by said control unit, a safety switch in control of said electrical device, said control unit having a starting position in which said first switch is open and said second switch closed, a first operating circuit for said control motor including a condition responsive switch and said second switch, the reaction between the rotor and stator upon the establishment of said operating circuit causing said rotor to rotate in one direction and said stator to rotate in the opposite direction against its bias to its second position, said control unit being moved by said rotor from its starting position toward a running position, said control unit closing said first switch as it moves from its starting position and then opening said second switch as it moves to an intermediate position to interrupt said first operating circuit for the control motor, operating means adapted to be moved in a certain path by said stator as it moves between its first and second positions, an actuator for said safety switch controlled by said control unit, said control unit normally keeping said actuator out of the path of movement of said operating means but moving said actuator into said path as said control unit reaches its intermediate position, interruption of said first operating circuit causing said stator to return to its first position under the influence of its bias if the control motor is deenergized at this time whereby said operating means engages said actuator and opens said safety switch, a second operating circuit for said control motor including a closed hot combustion switch, said last named circuit preventing deenergization of said control motor at the intermediate position of said control unit provided combustion is established before said control unit reaches its said intermediate position, and means for stopping said control motor when it reaches its running position.

16. In a motor operated fuel burner control system, a control motor having a rotor and a stator, said stator being rotatable coaxially with said rotor between first and second positions, means biasing said stator to its first position, a control unit, reduction gearing through which said control unit may be operated by said rotor, an electrical device which, when energized, causes the delivery of fuel to a burner, a first switch in control of said last named device operated by said control unit, a second switch operated by said control unit, a safety switch in control of said electrical device, said control unit hav-

ing a starting position in which said first switch is open and said second switch closed, a first operating circuit for said control motor including a condition responsive switch and said second switch, the reaction between the rotor and stator upon the establishment of said operating circuit causing said rotor to rotate in one direction and said stator to rotate in the opposite direction against its bias to its second position, said control unit being moved by said rotor from its starting position toward a running position, said control unit closing said first switch as it moves from its starting position and then opening said second switch as it moves to an intermediate position to interrupt said first operating circuit for the control motor, operating means adapted to be moved in a certain path by said stator as it moves between its first and second positions, an actuator for said safety switch controlled by said control unit, said control unit normally keeping said actuator out of the path of movement of said operating means but moving said actuator into said path as said control unit reaches its intermediate position, interruption of said first operating circuit causing said stator to return to its first position under the influence of its bias of the control motor is deenergized at this time whereby said operating means engages said actuator and opens said safety switch, a second operating circuit for said control motor including a closed hot combustion switch, said last named circuit preventing deenergization of said control motor at the intermediate position of said control unit provided combustion is established before said control unit reaches its said intermediate position, a fixed stop, means associated with said control unit engaging said fixed stop to stall said control motor when said control unit reaches its running position, a return switch, a latch therefor, actuating means associated with said stop and latch, said actuating means being in the path of said operating means whereby if said control motor is deenergized said operating means will engage said actuating means which will remove said fixed stop and latch said return switch and reenergize said control motor, and means operated by said control unit for moving said actuating means out of the path of said operating means and tripping said latch when said control unit reaches its starting position.

17. In a motor operated fuel burner control system, a control motor having a rotor and a stator, said stator being movable with respect to said rotor between first and second positions upon energization of said motor, means biasing said stator to its first position, switching means positioned by said rotor when the motor is energized, an electrical device which when energized causes the delivery of fuel to a burner, a safety switch, a main controller, means including said main controller for initiating energization of said control motor to cause said stator to move against said biasing means from said first to said second position and to cause rotation of said rotor, means including said safety switch and the switching means positioned by said rotor for causing energization of said electrical fuel controlling device, and means positioned by the movement of said stator to said first position upon deenergization of said motor within a predetermined range of the rotation of said rotor to open said safety switch.

18. In a motor operated fuel burner control

system, a control motor having a rotor and a stator, said stator being movable with respect to said rotor between first and second positions upon energization of said motor, means biasing said stator to its first position, switching means positioned by said rotor when the motor is energized, an electrical device which when energized causes the delivery of fuel to a burner, a safety switch, a combustion responsive device having cold and hot switches, a main controller, an energizing circuit for said motor including said main controller and the cold switch of said combustion responsive device for initiating energization of said control motor to cause said stator to move against said biasing means from said first to said second position and to cause rotation of said rotor, means including said safety switch and the switching means positioned by said rotor for causing energization of said electrical fuel controlling device, means including said switching means positioned by said rotor for interrupting the energizing circuit for said motor through the cold switch of the combustion responsive device and for establishing a new circuit to said motor through the hot switch of said combustion responsive device if combustion has occurred, and means for opening said safety switch by the movement of said stator to said first position if said hot switch is open at the time said energizing circuit is interrupted.

19. In a motor operated fuel burner control system, a control motor having a rotor and a stator, said stator being movable with respect to said rotor between first and second positions upon energization of said motor, means biasing said stator to said first position, a switch actuated by said stator when moved to said second position, an electrically operated fuel feeding device for a burner, ignition means for said burner, means positioned by said rotor for controlling the energization of said fuel feeding device and said ignition means, means for controlling the energization of said control motor including a main controlling switch having two pairs of sequentially engaging contacts, an initial energizing circuit for said control motor including both of said pairs of contacts, and a maintaining circuit for said control motor including only the first to be engaged of said sets of contacts and said switch actuated by said stator.

20. In a control system, a control motor having a rotor capable of continuous rotation and a stator, said stator being substantially instantly movable with respect to said rotor between first and second positions upon energization of said motor, stops to confine said stator to movement between said first and second positions, means biasing said stator to said first position, a switch actuated by said stator when moved to said second position, a reduction gear train, a driven member in place thereof positioned by said rotor through said gear train, means for controlling the energization of said control motor including a main controlling switch having two pairs of sequentially engaging contacts, an initial energizing circuit for said control motor including both of said pairs of contacts, and a maintaining circuit for said control motor including only the first to be engaged of said sets of contacts and said switch actuated by said stator.

JOHN M. WILSON.

CERTIFICATE OF CORRECTION.

Patent No. 2,377,535.

June 5, 1945.

JOHN M. WILSON.

It is hereby certified that error appears in the printed specification of the above numbered patent requiring correction as follows: Page 5, first column, line 7, for "unti" read --unit--; page 9, first column, line 27, for "of" after "bias" read --if--; and second column, line 63, strike out the words "in place thereof"; and that the said Letters Patent should be read with this correction therein that the same may conform to the record of the case in the Patent Office.

Signed and sealed this 2nd day of October, A. D. 1945.
